UNITARY TRANSFORMING AND CIRCUIT INTERRUPTING APPARATUS

Application filed May 18, 1929. Serial No. 364,175.

This invention relates to transformer substations of relatively moderate power capacity which are adapted to be energized from a high potential power source, as a long distance transmission line.

A transformer substation necessarily includes a stepdown transformer and a high potential circuit interrupter connected in the high tension leads to the transformer, both of which, usually, are rather expensive pieces of apparatus. An oil-immersed circuit interrupter, such as is suitable for the purpose, commonly includes a pair of high tension insulating bushings for each phase. These bushings, which must be widely spaced to provide adequate insulation in air between the conductors outside the switch enclosing casing, consequently increase the lateral dimensions of the switch very considerably over those which are necessary to insulate the live parts immersed in the insulating oil within the casing. An increase in the size of the casing necessarily results in an increased expense.

It is an object of the present invention to provide a high tension circuit interrupter for a transformer substation which has no exposed high tension insulating bushings and in which all the live conducting parts are immersed in oil whereby to reduce the overall dimensions of the interrupter.

Another object of the invention is the provision of a circuit interrupter for a transformer substation wherein the high tension line terminals and the line conductors connected therewith are immersed in a quiescent body of insulating fluid.

Insulating bushings which are capable of insulating a conductor at a very high potential in air are not only undesirable because of their relatively great size and the consequent increase in the dimensions of the switch casing but they are also very expensive to manufacture. An ordinary three phase circuit interrupter requires six bushings and these comprise a very material part of the total cost of the switch.

Consequently it is an object of this invention to provide a stepdown switching and transforming installation, suitable for an in-

dustrial customer's substation in which the number of high tension bushings is minimized and which is much less expensive than has formerly been commercially possible.

A further object of the invention is the provision of a high tension transformer and circuit interrupter unit wherein the bushings for the high tension side of the transformer serve to insulate the high tension leads for the interrupter, thereby eliminating all large and expensive bushings for the interrupter.

A yet further object is the provision of a transformer and circuit interrupter unit wherein the terminals and high tension leads of the interrupter are immersed in the oil of the transformer and the stationary and movable switch members are immersed in a second body of oil which is out of fluid communication with the oil in the transformer.

Another object of the invention is the provision of a transformer and interrupter unit wherein the contact members of the interrupter are accessible from outside the transformer casing and can be examined and repaired while maintaining inviolate the body of insulating oil about the switch terminals and the transformer.

A further object of the invention is the provision of a transformer and interrupter unit wherein the interrupter is located in two compartments carried by the transformer one of which is in free fluid communication with the transformer casing and the other of which is in free fluid communication with the atmosphere.

A yet further object of the invention is the provision of a transformer casing having a corrugated side wall provided with a plane portion for the attachment of a circuit-interrupter casing, the interior of which is in fluid intercommunication with the transformer casing.

A further object of the invention is generally to improve the construction and performance of electrical distribution systems and apparatus.

Fig. 1 is a perspective view of a transformer-interrupter unit embodying the invention and suitable for industrial customer or rural substations.

Fig. 2 is a sectional elevation of the substation of Fig. 1.

Fig. 3 is a plan view of the corrugated casing wall of the transformer showing the 5 plane or blank wall portion to which the interrupter casing is adapted to be attached.

The substation embodying this invention includes an oil immersed multi-phase step-down power transformer A having associated therewith a high tension oil immersed 10 circuit interrupter B which is adapted to control the flow of current between the incoming high tension leads and the primary windings of the transformer.

15 Said power transformer includes an oval oil containing casing or shell having the side wall 10 which is provided with heat-radiating corrugations 11 and the bottom wall 12 on which the core 14 and the associated windings 16 of the transformer are supported. Endless metal bands 18 and 20 overlie the upper and lower sinuous edges of said corrugated side wall 10 and are secured thereto in a fluid tight manner by welding. Said 25 bottom wall 12 is adapted to be secured permanently to said lower band 20 by welding. A cover 22 is provided at the top of said casing which is secured removably and in a fluid tight manner to said upper band 18 by means 30 of bolts 24. Said cover 22 is preferably crowned and supports at one side thereof the three similar upstanding and outwardly-inclined high tension insulating bushings 26. Said high tension bushings are provided with 35 exposed terminals 28 at their upper ends to which the phase leads of a three phase high tension power source are adapted to be separately connected. Corresponding low tension bushings 30 are provided at the opposite 40 side of the transformer casing having upper exposed terminals 32 which are adapted to be connected with the low tension distribution circuit and having lower terminals 34 beneath the body of oil within the transformer casing which are connected with the low tension 45 leads of the windings 16 of the transformer.

In accordance with the present invention, 40 the side wall 10 is formed from a blank or plane metal sheet of suitable dimensions which is suitably corrugated, as by passing it through suitable crimping rolls, to a point D adjacent one end whereby to provide a blank or plane portion 36 at one end thereof. The sheet is thereupon bent to the oval shape of Fig. 3 and the vertical edges thereof are welded at E to provide a continuous oil tight enclosure having the blank or plane side wall portion 36 extending from the top 55 to the bottom of the casing, the remainder of the wall being corrugated. Said blank wall is provided near the top thereof with a rectangular aperture 38 within which the open side of a rectangular casing F is received thereby forming a closure for said

aperture and providing an oil-containing, conductor-receiving chamber at the side of said transformer casing. An outstanding peripheral flange-member 40 is secured as by welding to the casing F and bolts 41 are passed through said flange and screw-threaded into the wall portion 36 whereby to secure said casing removably to said transformer casing. A suitable gasket may be placed between the flange 40 and the casing wall of 75 the transformer in the customary manner to insure a fluid tight joint thereat.

Said casing F comprises the switch frame for the three phase oil immersed circuit interrupter and to this end the bottom wall 80 42 thereof is provided with three pairs of laterally spaced apertures 43 in which are located the similar pairs of upright insulating bushings 44 and 46 which comprise the stationary switch members of the interrupter. Said bushings are provided with separate attaching flanges 48 by which they are secured in a fluid tight manner to said bottom wall 42 of the casing, and are further provided with axial conducting studs 50 85 which provide upper terminals 52 and 54 and which are terminated at their lower ends in fixed contact blocks 56. Said terminal members 54 are separately connected electrically through conductors 55, one of which is shown in Fig. 2, with the corresponding phase terminal 56 of a high tension transformer bushing 26. The other interrupter terminal members 52 are separately connected electrically through conductors 58, but one of which is shown in Fig. 2, with the corresponding phase lead of the high tension portion of the winding 16 of the transformer.

The terminals of the interrupter, including the upper portions of the bushings which are customarily exposed in air, by this construction are wholly immersed in the quiescent body of insulating oil C which occupies the casing F and the transformer casing A. 100 The conducting leads attached to said bushings are also immersed in and insulated by said oil. Thus, the bushings can be small and consequently cheap, as compared with the usual construction.

An oil containing receptacle G is secured detachably to the bottom of the wall 42 of casing F and depends therebelow whereby to enclose and submerge the live parts of said depending stationary switch members in insulating oil. A movable switch member including the bridging or brush member 60 is adapted to separately bridge the pairs of stationary contact blocks 56 of the interrupter within said receptacle G whereby to complete the circuit through the switch in the usual way. There is a separate bridging member 60 for each phase of the switch and all bridging members 60 are adapted to be moved simultaneously by means of sepa-

rate lifting rods 62 which extend upwardly through individual tubes or passages 64 through the casing F and are operatively connected with suitable switch operating mechanism which is indicated diagrammatically by the crank arm 66. The passages 64 are adapted to be free from communication with the casing F. Each of said passages may consist of a section of pipe extended through the top and bottom walls of casing F and having an internal diameter somewhat greater than the diameter of the lifting rods 62, which pipe may be welded at its upper and lower peripheral ends to 10 the top and bottom walls of said casing in a fluid tight manner. It will thus be evident that the lower oil containing receptacle G is free from fluid communication with the casing F. Preferably a gas expansion 20 space 67 having a vent 68 open to the atmosphere, is provided in the upper portion of said receptacle.

A mechanism housing H is provided about the open tops of the passages 64 and 25 encloses the switch operating mechanism.

It will be evident from the above description of the invention that all live conducting parts of the interrupter are wholly immersed in oil and that, as a result, the insulating 30 bushings 44 and 46 of the interrupter need be very small compared with the usual bushings such as the high tension bushings 26 of the transformer, which are necessary to insulate the conductors in air. Obviously the 35 spacing of the bushings can also be greatly reduced, since the presence of a quiescent body of oil about the terminals 52 and 54 and the leads 55 and 58 greatly decreases the strike-over distance over that which must be 40 provided in air.

Those parts of the interrupter, as the co-operating contact members, which are subject to impairment in service are readily accessible without disturbing the body of insulating oil within the transformer. Furthermore, the body of oil within the transformer, being entirely separate from that surrounding the separable switch members in the 45 interrupter, can never become fouled from the products of circuit interruption and the deleterious action of the arc thereon.

The substation above described is particularly suitable for industrial customer substations since it is relatively inexpensive to manufacture and comprises a unitary construction which can be shipped as such. The elimination of six high tension bushings comparable in size and expense with the bushings 50 26 of the transformer effects a marked reduction in the first cost of the installation as well as in subsequent operating costs.

The construction may be modified in many ways without exceeding the scope of the invention.

I claim:

1. A unitary substation including a transformer having an enclosing casing adapted to contain a body of oil, a second enclosing casing connected with said transformer casing having separate upper and lower compartments, said upper compartment only being in free fluid communication with the transformer casing, an electric switch for the circuits of said transformer having separable 70 contact members contained in said lower compartment and operating mechanism for said switch operating through said upper compartment.

2. A unitary substation including a transformer having an enclosing casing adapted to contain a body of insulating oil, a switch casing associated with said transformer casing having two separate compartments, one of which compartments is freely open into the 80 transformer casing and the other of which is separated from fluid communication therewith by a fluid tight barrier, cooperating circuit controlling contact members contained in said latter compartment, and operating mechanism 85 for said contact members which is external of both casings and has an operating member that is extended through said upper compartment into said first compartment.

3. A unitary substation apparatus including a main transformer enclosing casing adapted to contain a body of oil, an interrupter enclosing casing having two separate compartments, one of which is next adjacent and is freely open into said transformer casing beneath the level of the oil therein, switch terminals disposed within said adjacent compartment and immersed beneath the oil therein and extended into the other of said compartments, said other compartment adapted 100 to contain a separate body of insulating oil in which said terminals are immersed, co-operating circuit interrupting contact members contained in said other compartment beneath the oil therein, and operating mechanism 105 for said interrupter which is extended through said first compartment into said second compartment and has means isolating it from the oil in said first compartment.

4. A unitary substation apparatus including a main transformer enclosing casing adapted to contain a body of insulating oil, an interrupter enclosing casing connected therewith and freely open into said transformer casing beneath the level of the oil 115 therein, said second casing having a partition therein providing two separate compartments only one of which is in fluid communication with said transformer casing, an insulating bushing common to both compartments and having a terminal at each end thereof disposed in a separate one of said compartments, 120 separable interrupter components disposed within said fluid isolated compartment, a separate body of oil contained therein be- 125 130

- neath which said components are immersed, said latter compartment having an extension which extends through and terminates above the oil in said first compartment, and operating mechanism for said interrupter having an operating member which extends through said extension into said latter compartment.
5. A unitary transformer and circuit interrupter apparatus including a transformer enclosing casing adapted to contain a body of oil, an interrupter enclosing casing attached to said transformer casing, said interrupter casing having an upper compartment which is freely open into said transformer casing beneath the level of the oil therein and a lower compartment which is isolated against fluid intercommunication with said upper compartment and transformer casing, said 10 lower compartment adapted to have a body of insulating oil therein and a gas expansion space above the oil, a conduit communicating with said gas expansion space and extended through said upper compartment and open 15 to the atmosphere at its upper end, separable contact members in said lower compartment and switch operating mechanism disposed in said conduit and connected with said contact members.
- 20 6. A unitary substation apparatus including a transformer enclosing casing adapted to contain oil, an auxiliary casing carried by a side wall of said transformer casing and having an opening into said transformer casing beneath the level of the oil therein, a vertical conduit extended through said auxiliary casing open at its upper and lower ends and having a peripheral fluid tight connection with the top and bottom walls of said 25 casing, an open top receptacle secured removably to said lower casing wall about the lower open end of said conduit, stationary interrupter members carried by said bottom casing wall and extended above said wall into 30 said casing and also below said wall into said receptacle, stationary contact members disposed within said receptacle and connected with said interrupter members, movable contact members cooperating with said stationary contact members, operating mechanism for said interrupter including an operating rod disposed in said conduit and connecting said mechanism with said movable contact member.
- 35 7. In testimony whereof, I have signed my name to this specification.

GUSTAV E. JANSSON.
